[57] CLAIM

The ornamental design for an air freshener, substantially as shown and described.

DESCRIPTION

FIG. 1 is a perspective view of an air freshener showing my new design;

FIG. 2 is a front elevational view thereof;

FIG. 3 is a right side elevational view thereof;

FIG. 4 is a top plan view thereof;

FIG. 5 is a bottom plan view thereof;

FIG. 6 is an enlarged scale cross sectional view taken on line 6—6 of FIG. 2; and

FIG. 7 is a rear elevational view thereof.

The broken line representation of a support stand in FIG. 1 is for purposes of illustration only.
